UNITED STATES PATENT OFFICE.

ALEXANDER FINLAY, OF PHILADELPHIA, PENNSYLVANIA, ASSIGNOR TO THE BARRY-MORE SEAMLESS WILTONS, INC., OF PHILADELPHIA, PENNSYLVANIA, A CORPORATION OF PENNSYLVANIA.

DESIGN FOR A CARPET.

Application filed July 29, 1927. Serial No. 22,949. Term of patent 7 years.

To all whom it may concern:

Be it known that I, ALEXANDER FINLAY, a citizen of the United States, residing in Philadelphia, Pennsylvania, have invented a certain new, original, and ornamental Design for a Carpet, of which the following is a specification, reference being had to the accompanying drawing, the figure of which is a face view of a carpet illustrating my new design.

I claim:

The ornamental design for a carpet, substantially as shown.

ALEXANDER FINLAY.
